UNITED STATES PATENT OFFICE.

HORACE L. WINSLOW, OF CHICAGO, ILLINOIS.

HEATING SYSTEM.

No. 888,773.

Specification of Letters Patent.

Patented May 26, 1908.

Application filed November 13, 1906. Serial No. 343,247.

To all whom it may concern:

Be it known that I, HORACE L. WINSLOW, a citizen of the United States, residing at Chicago, county of Cook, State of Illinois, have invented a certain new and useful Improvement in Heating Systems, and declare the following to be a full, clear, and exact description of the same, such as will enable others skilled in the art to which it pertains to make and use the same, reference being had to the accompanying drawings, which form a part of this specification.

My invention relates in general to heating systems, and more particularly to a system of uniformly distributing heated air throughout an inclosed space.

It is well known that as hot air rises the air near the ceiling of a room is hottest, and that near the floor is coolest. It is therefore desirable that the air should circulate downwardly in order that the temperature of the room, or other inclosed space, may be uniform. It is also desirable that the air should be withdrawn from the coldest parts of the room, as for instance adjacent windows and doors, and replaced by hot air, in order that air may be at a substantially even temperature throughout the room.

The primary object of my invention is to provide an apparatus for heating rooms, or other inclosed spaces, by means of which air will be withdrawn from cold points within the room, and hot air supplied to such points to replace the withdrawn cold air, thereby uniformly distributing the hot air throughout the room.

A further object of my invention is to provide a heating apparatus by means of which the temperature within an inclosed space may be maintained at an even temperature throughout at a minimum cost.

A still further object of my invention is to provide a heating system which will be simple in construction, economical in operation, and by means of which hot air may be evenly distributed throughout a room or other inclosed space.

The embodiment of my invention herein disclosed may be generally described as comprising a heating chamber located centrally within the inclosed space which is to be heated, air supply conduits communicating with the bottom of the chamber and leading from remote points adjacent the floor of the room, a blower located within the bottom of the chamber for drawing the air from the supply

conduits and forcing the same upwardly through the chamber, heat radiating surfaces within the chamber around which the air is forced, hot air delivery flues leading from the top of the chamber to distant points within the room, such points being preferably remote from the points from which the conduits lead, whereby the hot air will be delivered at certain points and then drawn to other points from which the air has been withdrawn through the conduits.

My invention will be more fully described hereinafter with reference to the accompanying drawings in which the same is illustrated as embodied in a convenient and practical form, and in which

Figure 1 is a vertical sectional view, the top thereof being shown in elevation; Fig. 2 a plan view; and Fig. 3 a cross-section taken midway between the top and bottom of the structure shown in Fig. 1.

The same reference characters are used to designate the same parts in the several figures of the drawings.

Reference character A designates the floor of a room or other inclosed space which is to be heated.

B designates the ceiling or top wall of the inclosed space.

While my invention is not limited in its application to any particular character of inclosed space, yet it is especially designed for heating large rooms such as factories.

C designates a heater for hot air which is located within the room preferably at a central point. The heater comprises a cylindrical chamber which may be made of any suitable material within which is located any desired means for radiating heat. I have shown for convenience two vertical headers E' and E² located within the chamber and connected by a plurality of parallel tubes E. Steam is supplied through a conduit e' to the header E' and thence passes through the connecting tubes E to the header E² and thence is discharged to the conduit e². The exhaust steam from engines may be economically used as the medium for heating the headers and connecting tubes.

Air supply conduits lead from various points within the inclosed space and communicate with the lower end of the heating chamber. These supply conduits may be of any suitable construction and are shown in the drawings as made of brick and located beneath the floor of the room.

Reference characters D', D², D³ and D⁴ indicate the air supply conduits radiating from the heating chamber and terminating at any points within the room where it is desired 5 that heat should be drawn, as for instance adjacent windows or doors. Gratings or registers d are located in openings in the floor above the ends of the supply conduits. If desired one or more of the conduits may be 10 provided with branches leading to various points within the room, as indicated in Fig. 2 in which the conduit D' is provided with branch conduits d', d², and d³. The combined capacity of the branch conduit should 15 then equal the capacity of the main conduit, while the aggregate capacity of the main conduits should be substantially equal to the capacity of the heating chamber C.

The inner ends of the supply conduits may 20 communicate with the bottom of the heating chamber in any desired manner, as for instance by extending through openings in the brick foundations C' upon which the heating chamber is supported.

25 The air is drawn from the supply conduits and forced upwardly around the radiating surfaces within the heating chamber by means of a blower or fan F which may be supported and rotated in any suitable manner. 30 I have shown the fan F as fixed upon a vertical shaft f supported in bearings in the brackets f' and f'' secured within the heating chamber.

35 F' designates a pulley wheel secured to the lower end of the shaft f by means of which the fan may be rotated.

Flues lead from the upper end of the heating chamber to points within the room where it is desired that hot air should be delivered. Reference characters G', G², G³, 40 and G⁴ designate such flues, which may be if desired provided with dampers g for regulating the discharge of hot air therethrough. The flues preferably extend from points adjacent the closed upper end c of heating chamber C and terminate at points distant from the point from which the air supply conduits extend.

45 The operation of my improved heating system is as follows: The cold air is drawn from various points within the room adjacent the floor and passes upwardly around the radiating surfaces within the heating chamber, such movement of the cold air to and through 50 the heating chamber being preferably promoted by the fan F. The hot air passes from the heating chamber through the flues

55 to the various points within the room, and from such points is drawn towards the ends of the air supply conduits to replace the air 60 which has been withdrawn from adjacent the floor of the room.

65 From the above description it will be observed that by my improved heating system the temperature within an inclosed space 70 may be maintained evenly inasmuch as the hot air is distributed at various points within the inclosed space and circulates from such points to the points where the cold air is withdrawn. It is also evident that the uniform distribution of the heat by drawing the hot air from the upper portion of the room toward the floor thereof results in the desired temperature being obtained with a 75 minimum consumption of heat.

80 While I have described more or less precisely the details of construction, I do not wish to be understood as limiting myself thereto, as I contemplate changes in form, the proportion of parts, and the substitution of equivalents, as circumstances may suggest, or render expedient without departing from the spirit of my invention.

85 Having now fully described my invention, what I claim as new and desire to secure by Letters Patent is:

1. In a system for heating an apartment, the combination with a heater, of a plurality of air supply conduits leading to said heater from separated points remote from the 90 heater and adjacent the floor of the apartment, and a plurality of flues for delivering hot air from said heater to separated points within the apartment, said delivery points being distant from said points of supply. 95

100 2. In a system for heating an apartment, the combination with a heater, of a plurality of air supply conduits leading to said heater from separated points remote from the heater and adjacent the floor of the apartment, a plurality of flues for delivering hot air from said heater to separated points within the apartment, said delivery points being distant from said points of supply, and means for promoting circulation of air through said supply conduits to the heater and from the heater through said flues. 105

In testimony whereof, I sign this specification in the presence of two witnesses.

HORACE L. WINSLOW.
